(57) **CLAIM**

We claim the ornamental design for a module of a heart rate belt, as shown and described.

DESCRIPTION

FIG. 1 is a top, rear perspective view of a module of a heart rate belt showing our new design;

FIG. 2 is an enlarged front, top perspective view of the module of FIG. 1;

FIG. 3 is an enlarged top view thereof; and,

FIG. 4 is an enlarged front view thereof.

The ornamental design that is claimed is shown in solid lines in the drawings. The broken lines in FIGS. 1-4 are included for the purpose of illustrating portions of the module of a heart rate belt that forms no part of the claimed design.
